United States Patent Office

Des. 187,929
Patented May 17, 1960

187,929

BOOKSTAND

Eberhard G. Rensch, Frankfurt am Main, Germany

Application May 26, 1959, Serial No. 56,070

Term of patent 14 years

(Cl. D33—2)

Fig. 1 is a perspective view of a bookstand embodying the present invention;

Fig. 2 is a side elevational view of the bookstand of Fig. 1; and

Fig. 3 is a top plan view of the bookstand of Fig. 1.

I claim:

The ornamental design for a bookstand, as shown.
